FOLDABLE AND EXTENSIBLE SOCK-STRETCHER AND DRIER

Filed March 17, 1943

UNITED STATES PATENT OFFICE

2,354,849

FOLDABLE AND EXTENSIBLE SOCK
STRETCHER AND DRIER

Mabel Dorsey Causer, Sarasota, Fla.

Application March 17, 1943, Serial No. 479,445

5 Claims. (Cl. 223—77)

This invention relates to sock-stretching and drying forms, and has for its primary object to provide a portable device of this character for both soldiers and civilians which can be manufactured in practically one standard uniform size, so that it may be supplied or presented to soldiers or others having varying unknown sizes of feet, being adjustable to all of them, and which may be folded up and mailed to distant points and conveniently carried in kit-bags.

One particularly that can be produced in large quantities not only at an irreducible minimum of expense, but also without requiring any often unobtainable skilled labor whatever. One that will be light, strong, efficient, with no mechanisms or contrivances apt to get out of order, to catch upon and tear the socks, to rust or corrode and stain them, to require replacement or repair at times and places where this is difficult.

One that can be manufactured merely of a few simple tough basic structural portions which may be struck simultaneously out of a single sheet of material or pile of sheets, combined with easily procurable and readily replaceable means of assembling, connecting and rendering them functionally operative, adjustable and foldable either in extended or retracted position, and without hindrance in mass-production in war-times due to any need to employ metals or other materials priority-directed to more essential war-offensive.

My invention consists of a form made in the shape of the human foot, in three pieces of plastic or Masonite or pressed board material, devoid of any metal whatever, devoid of any auxiliary parts or appendages of a metallic or hard or other machined or cast material, assembled together in one unitary device by means of an insertible, detachable and flexible hinge means as to the upper and middle sections, and by a combined hinging, assembling, detachable, extensible, foldable means as to the middle and toe sections; one form or embodiment of such invention and principle is illustrated and described hereinafter.

I am aware, since the completion of my invention, that there have been devised past attempts at a foldable and extensible sock-stretcher, but none of these shows or describes or has claimed to have invented, and there is not now or ever has been on the market, so far as I know, any device of this nature which, (a) has been manufactured out of plastic or pressed board without appendages, and yet is foldable and extensible; (b) or any which can be made without metals and yet is foldable and extensible; (c) or any

which has my idea, principle and invention of a stretcher which is assembled, hinged, and made extensible and foldable all by the one means or expedient; (d) any which does not rust or tear the goods or have protruding parts to hinder hauling, and yet is both foldable, extensible, detachable; (e) any device whatever which will stretch all sizes of socks, that can be manufactured today in war times, owing to priority bans on materials required to make any and all known inventions of this nature, and to the impossibility of getting such parts manufactured today.

In the accompanying drawing forming part hereof:

15 Figure 1 is a side elevation of the sock-stretcher and drier in operative position partially extended, ready for the sock.

Figure 2 is a section thereof on the line 2—2, of Fig. 1.

20 Figure 3 is a detail of the extension device, under side.

Figure 4 is a small detail section on the line 4—4, Fig. 1.

25 Figure 5 is an edge elevation of the device, folded.

Figure 6 is a reduced perspective elevation of the device, so folded.

My improved sock-stretcher and drier is composed of a plurality of sections 1, 2, and 3, of flat water-and moisture-proof material such as Masonite, pressed-board or plastic, struck out from a sheet or pile of sheets of the selected material by dies, or jig-sawed out of such a pile.

30 These three sections are of the shapes shown in the drawing, and when laid together comprise a form having the contour of a human foot in profile or a flattened sock, all of a predetermined size to be best adapted to a wide range of varying feet; it being desirable to make the central and toe portions of the form amply wide for lateral stretching of the foot-wear, and the upper end of the leg-portion not too wide, because it is not usually desired to stretch this part of the sock and so impair its snugness.

35 The sock-stretcher is thus divided into the upper or leg-section 1, the middle or angle-and-heel-section 2, the toe-and-ball-section 3; herein called, for brevity and clarity, the leg-section 1, ankle-section 2, toe-section 3. The length of each is arranged so that the end-sections fold neatly upon the middle one, which is left a solid one-piece heel-and-ankle form for the important shaping of that portion of the sock which is conventionally full-fashioned, or which in less well-

made foot-wear may be substantially so shaped in drying or stretching.

The leg-section 1 is provided with a series of aligning eyelet-holes 4 near its lower edge; and the ankle-section 2 is provided with a corresponding series of oppositely-registering eyelet-holes 5 near its upper edge. These are holes punched in the sheet material when the sections are struck out, or may be punched in afterward, and do not require any bushings.

The respective edges of the two sections 1 and 2 are connected and held in abutment and pivotally movable relatively, by a uniting and hinging lacing 6 inserted and drawn through the oppositely-disposed eyelet-holes 4 and 5, which permits the folding of one section upon the other. The lacing is inserted from the under side of the sections to the upper faces thereof, across their junction, and tied in bow-knot 7.

The lower end of the ankle-section 2 is provided near its edge with two parallel series of aligned eyelet-holes 8 and 9. The toe-section 3 is provided near its upper edge with two similar series of parallel eyelet-holes 10 and 11, which oppositely register with the eyelet-holes 8 and 9 of the ankle-section 2 when the two sections are held in abutting position, and correspondingly register upon and over the said eyelet-holes when the two sections overlap.

These two sections 2 and 3 are connected and retained in various possible positions by a lacing 12 inserted and drawn through the eyelet-holes of each section, from underneath to upper face and back. If the laces are drawn tightly, the sections are held more firmly together, but if not drawn too tightly, the sections may be folded one upon the other without first untying the bow-knot 13, in which it is tied at its ends.

It will be obvious that by untying and removing the lacing 12, and adjusting and extending the toe-section 3 upon the ankle-section 2, or retracting it, so that the length of the form is altered, and reinserting and retying the lacing 12, the device is capable of stretching socks of varying sizes, while yet the extension-adjustment factor permits folding of the sections in all their adjustments, indeed is itself the sole hinging expedient.

By extending the device so that the edges of the two sections abut and do not overlap, the greatest length of the stretcher is reached, to receive the largest sock of the range of sizes taken care of. Conversely, to produce a slightly shorter extension of the foot-portion of the sock, the sections 2 and 3 are brought to overlap so that eyelet-holes 8 register upon eyelet-holes 10, the lacing 12 being changed to hold them together.

Again changing the lacing, and moving the ankle-section 2 and toe-section 3 further together, until eyelet-holes 8 register upon eyelet-holes 11, and eyelet-holes 9 upon eyelet-holes 10, and reinserting the lacing, a still shorter adjustment of length is achieved. And by still further overlapping the sections until eyelet-holes 9 register upon the eyelet-holes 11, the lowest adjustment of the foot-portion is found.

In the abutting position of the sections, offering the maximum extension, the lacing 12 engages only the two oppositely-adjacent eyelet-holes of the two sections; in the slightly-shorter adjustment, the lacing passes through one series of eyelet-holes in one section and two series in the other; in the next shorter adjustment, it engages two series in each section; and in the

lowest adjustment, it passes through eyelet-holes 9 and 11 only. But this is merely the best mode of usage, and the lacing may be used as desired.

In folding the toe-section over upon the ankle-section, if the easier-folding position of abutting edges or maximum length is not being used, it is desirable that the toe-section be under the ankle-section, with the latter overlapping, since then the folding is more easily accomplished than if the toe-section overlaps the ankle-section, in which position it will be found more difficult to fold, and the lacing 12 will need to be well loosened to allow it; the best rule being by all means to place the toe-section always underneath. The device folds in any overlapping adjustment, as well as when abutting, even with the sock on.

The number of the parallel series of eyelet-holes 8 and 9, and 10 and 11, in the ankle-section and the toe-section respectively, is not limited; there may be additional lines of these eyelet-holes, and the spacing of them may be such as to permit of more numerous adjustments in shorter steps or longer, as deemed best. Thus the limits of extension may be enlarged to almost any reasonable degree. I find, however, that the arrangement shown, with two series on each section, is ample to cover all likely requirements.

Each section is provided with one or more ventilating holes 14, and the leg-section 1 with a hole 15 for hanging the stretcher up with the sock on it, all as is usual in devices of this nature. Two socks may be dried on one stretcher, one drawn on over the other, or a pair of forms may be employed. The socks are usually washed first, wrung out, and applied upon the stretcher to dry, having adjusted it to suit the length needed. They may also be placed upon the stretcher when just off the feet, damp from wearing, or socks already dried and too much shrunken, may be dampened and pulled on the stretcher. In all cases, the device dries and stretches the whole sock, except the upper leg-portion, and the solid ankle-section 2 shapes the entire heel-portion to fit well and stay on the foot better.

While I have shown and described my invention in the embodiment hereinabove set forth, I desire it understood that my invention, and the principle thereof, embraces any non-metallic, flexible, and single, unitary, quadro-functional means for, at the one operation and with the one mechanical expedient, assembling the adjacent parts together at the junction of the toe and ankle-sections, hinging them, rendering them extensible, and rendering them detachable, and enabling the said assembling, hinging, extending, and detaching unitary means to be replaced when worn out, by means of which principle, idea and invention I have produced the only device of this character capable of accomplishing the objects specified by me in the preamble to this specification. I have for this purpose devised the expedient of arranging the toe-section adjustably upon the ankle-section, providing each such section with simple, non-protruding, non-metallic means for registering them in several alternative positions of adjustment, and connected them together for the quadro-functional purposes above-indicated, by a flexible lacing adapted as like simple, non-metallic, non-injurious means for retaining them in such adjustment. This invention of mine, as thus defined, is novel and is the only way known up to now

to produce any extensible and foldable sock-stretcher achieving the purposes and performing the functions of my invention; and I hold this principle as new and original and of my own devisement, within the spirit and scope and purview of my hereinafter appended claims.

The advantages of my invention will be manifest after this description of its structure and operation, if reference be had to my statement at the outset, of the objects of the invention, which it will now be seen are fully accomplished.

Having thus described my invention, what I claim as new and desire to secure by Letters Patent is:

1. A foldable and extensible sock-stretcher and drier, comprising exactly three sections which combined form a complete form of the entire shape of a foot flattened, without extra appurtenances, namely, a hinged upper leg section, a central unbroken heel, ankle and instep section, and a lower section comprising in one portion all of the remainder of the foot portion and the toe portion; the said lower section overlapping the central section, and both being provided with an adjustment and extension means whereby the lower foot section fits and sets in three distinct extension positions, the first an overlapping minimum short size, the second an overlapping materially larger size, and the third an abutting maximum size in which the sections do not overlap but lie in the same plane edge against edge; and a single means for simultaneously hinging the said two sections foldably and in any one of the three positions extended or retracted, with the sock or socks thereon stretching and folded away.

2. A foldable and extensible sock-stretcher and drier comprising exactly three sections which combined form a complete implement of the entire shape of a foot flattened, without extra appurtenances, projections or protrusions, namely, a hinged upper leg section, a central unbroken heel, ankle and instep section, and a lower section comprising in one portion all the remainder of the foot-portion and the toe portion; the said lower section overlapping the central section, and both formed to be extended in both overlapping and abutting adjustment and extension, whereby the lower foot and toe section fits and sets in three distinct extension positions, the first an overlapping minimum short size, the second an overlapping materially larger size, and the third an abutting maximum size in which the sections do not overlap but lie in the same plane edge against edge; and a single unitary combined hinging and assembling and adjustment retaining means, which is inserted in through the central and lower sections removably and interchangeably to simultaneously assemble, hinge foldably, and retain said two sections together in any one of the three alternative adjustment positions, whereby said stretcher may be folded with a sock or socks on it, in any one of said three extension adjustments, and put or packed away folded.

3. A foldable and extensible sock-stretcher and drier, comprising a plurality of separate sections of flat material which when placed together compose a foot-form comprising an upper or leg section, a central section including both the heel and ankle and instep portions and a lower toe section, the toe-section and the ankle-section being each adjustably mounted one upon the other with the toe-section overlapping the ankle-section upon one surface of said ankle-

section, whereby the said toe-section may both fold over upon said ankle-section either above or below the same, and may at the same time be adjusted in length longitudinally of the foot-form without altering the heel or instep or ankle of the form, and may be folded over the said ankle-section in any adjustment of said length relatively to the same, and being provided with non-protruding means for registering together in any one of several longitudinally extensible positions; and a single non-metallic means for simultaneously assembling or connecting said parts together, for hinging them in foldable relation, for retaining them in adjusted position, or any of such several adjustments, and for enabling the detachment and replacement of such attachment and hinging and retention means, whereby a sock of any of several sizes may be stretched upon said form, and the form folded in any of said several longitudinal adjustments with the said sock thereon; and the upper leg-section being hinged to said ankle-section at the upper edge of the latter, by a single non-metallic means for attaching said sections together, the said hinging means being also replaceably removable.

4. A foldable and extensible sock-stretcher and drier, comprising a plurality of separate sections of flat material which when placed together compose a foot-form, comprising an upper or leg-section, a central section including both the heel and ankle and instep portions and a lower toe-section, the leg-section being hinged to the ankle-section by a single assembling, connecting, detachable non-metallic means; the ankle-section at its opposite end, and the toe-section, being adjustably mounted one upon another, with the toe-section overlapping the ankle-section upon one surface of said ankle-section, whereby the said toe-section may both fold over upon said ankle-section either above or below the same, and may at the same time be adjusted in length longitudinally of the foot-form without altering the heel or instep or ankle of the form, and may be folded over the said ankle-section in any adjustment of said length relatively to the same, and being provided with means for registering them mutually together in any of several longitudinal adjustments to fit various lengths of foot with the one appliance, the said registering means being within the borders and substance of the two sections, non-metallic and non-protruding; and a single unitary, non-metallic, insertible, detachable means for simultaneously assembling, and connecting, hinging, holding in adjusted position or extension, holding in foldable position in any adjustment, the said toe-section and ankle-section, whereby a sock or socks of any of several sizes may be stretched upon said form, and the form folded in any of said several longitudinal adjustments with the said sock or socks thereon; the hinging means for assembling the leg-section and the ankle-section together in hinged relation being detachable by the user, and the said unitary means for assembling, hinging, holding folded, and holding in adjusted or extended position the said ankle-section and the toe-section, being flexible and operable as such single unit in any such extended or retracted position of said toe-section.

5. A foldable and extensible sock-stretcher and drier, made in three sections of flat material which when placed together compose a foot-form, the toe-section and the ankle-section being

connected together by a single unitary means for simultaneously assembling, connecting, hinging in foldable relation, retaining in any of several longitudinal extended relations, and easily permitting the detachment of said parts, whereby the device may be employed for a number of sizes of socks, may be assembled, and folded in extended or retracted positions, and its said folding, extension-retaining means replaced from time to time by the user; the said single unitary means for so doing comprising a long inseparable lacing, embracing the edges of the

ankle-section and the toe-section, extending through both said edges, and the said edges each being provided with two series of eyelet-holes arranged when registered mutually, to establish several foot-lengths of said foot-form, in which extension relation they remain held by said lacing in such manner that they are foldable with the sock or socks thereon in any of the several extended positions fitting the sock or socks being stretched and dried thereon.

5
10

ankle-section and the toe-section, extending through both said edges, and the said edges each being provided with two series of eyelet-holes arranged when registered mutually, to establish several foot-lengths of said foot-form, in which extension relation they remain held by said lacing in such manner that they are foldable with the sock or socks thereon in any of the several extended positions fitting the sock or socks being stretched and dried thereon.

MABEL DORSEY CAUSER.
